ESCUTCHEON PLATE

Raymond U. H. Tegner, Lodi, Wis. (½ Amerock
Corporation, 4000 Auburn St., Rockford, Ill. 61101)

Filed Nov. 10, 1972, Ser. No. 305,567

Term of patent 14 years

Int. Cl. D8—09

U.S. Cl. D8—181

fig. 3.fig. 5.

FIG. 9.

FIG. 10.

FIG. 1 is a front view of an escutcheon plate showing my new design as incorporated in a single switch plate.

FIG. 2 is a side view as seen from the right of FIG. 1.

FIG. 3 is a bottom view of the plate.

FIG. 4 is a sectional view taken along the line 4—4 in FIG. 1.

FIG. 5 is a sectional view taken along the line 5—5 in FIG. 1.

FIG. 6 is a front view of a modified form of an escutcheon plate showing my new design as incorporated in an electrical receptacle plate and having a bottom view and a sectional configuration generally similar to that shown in FIGS. 3 and 5.

FIG. 7 is a sectional view taken along the line 7—7 in FIG. 6.

FIG. 8 is a front view of another modified form of an escutcheon plate showing my new design as incorporated in a combined switch and receptacle plate and having an end view and sectional views generally similar to those shown in FIGS. 3, 4 and 5 but varying in accordance with the width of the plate.

FIG. 9 is a front view of a triple switch plate incorporating my new design and having a sectional view similar to FIG. 4 and a sectional view similar to FIG. 5 except proportioned according to the width of the plate.

FIG. 10 is a bottom view of the plate shown in FIG. 9.

I claim:

The ornamental design for escutcheon plate, as shown and described.
